LOCOMOTIVE STOKER

Original Filed Feb. 5, 1932

UNITED STATES PATENT OFFICE

1,993,303

LOCOMOTIVE STOKER

John W. Myers, Roanoke, Va., assignor to The Standard Stoker Company, Incorporated, a corporation of Delaware

Application February 5, 1932, Serial No. 591,125
Renewed January 2, 1934

14 Claims. (Cl. 198—15)

This invention which relates to locomotive stokers has for its chief object the provision of a flexible and sectional stoker conduit system wherein there is no longitudinal movement between the conduit sections, but which conduit system is installed on the locomotive and its tender to permit of movement between the rearward or transfer conduit section and the tender, while, at the same time, providing for all other movements necessary when the locomotive and tender are negotiating curves, cross-overs or turntables.

In carrying out the chief object of this invention, the fuel transfer conduit is pivotally mounted upon a vertical axis, mounted for slidable movement longitudinally of the tender and fixed with references to movement about a horizontal, transversely extending axis.

In its more specific aspect the object of this invention contemplates the provision, in a stoker having a novel transfer conduit disposed on the tender as described, a novel relation of the fuel conveying conduits which consists in joining one end of the stoker intermediate to the riser conduit of the locomotive, while the other end of the intermediate conduit is jointed to the fuel transfer conduit so as to swing upon a transversely extending axis.

These and further objects which reside in the provision of an improved stoker fuel conveying system will become apparent when the following specification is read in connection with the accompanying drawing, in which

Figure 1 is a central vertical longitudinal section through adjacent portions of a locomotive and tender with the invention partly in similar section and partly in elevation;

Figure 2 is a sectional view taken on the line 2—2 of Figure 1; and

Figure 3 is a fragmentary view similar to Figure 1 showing a modified form of the invention.

Referring now to Figures 1 and 2, the locomotive is shown at 10, its firebox at 11, which is provided with the usual backhead 12 having a firing opening 13 therethrough. Coupled to the locomotive as at 14 is a tender 15 which is provided with a frame 16, and the fuel bin 17, the latter being disposed above the deck 18 which is apertured as at 19 to allow fuel to fall into the open mouthed trough 20.

The means for transferring fuel from the fuel bin to the firebox includes a conveying system S which is comprised of a fuel transfer conduit T, a riser conduit 21 and an intermediate conduit section 22 which serves to connect the first and

second named conduit in a novel end to end relation as will become apparent.

The transfer conduit T includes the trough member 20 which is provided with a saddle member 23 intermediate its ends. The saddle member 23 is rigidly secured to the trough member and has a flat plate-like portion 24 depending therefrom which rests upon a bracket 25 rigidly secured to the tender frame 16. The bracket 25 is provided with a longitudinal slot 26 through which the vertical shaft or pivot 27 passes for engaging the plate-like portion 24 of the saddle member. The outer extremities of the shaft or pivot 27 are provided with threaded caps 28 and 29 which may be tightened or loosened in a manner to permit the saddle member 23 and the trough member 20 to pivot about the shaft 27 and move longitudinally with respect to the tender and bracket 25 and at the same time, prevent any vertical movement of the trough with respect to the tender frame 16. The trough member 20 may be further supported by pedestals such as 30 which may be secured either to the bracket 25 as shown or to the tender frame 16, the trough member 20 being free to slide upon this pedestal.

Secured to the front wall 31 of the trough member 20 is a connecting member 32 which has a tubular portion 33 thereof communicating with the opening in the front wall 31. The forward extension of this connecting member is substantially U-shaped in vertical transverse cross section, having the parallel side-walls 34, 35 and the arcuate shaped bottom wall 36 which is also of similar form in its vertical longitudinal section. The forward extension of the connecting member 32, may, if desired, be provided with a top wall 37 which has an enlarged section 38 to receive a horizontal, transversely extending shaft 39.

Depending from the extremities of the shaft 39 by its sidewalls 40, 41, is the rearward portion 42 of the intermediate conduit 22. The portion 42 is also U-shaped in vertical transverse cross section and has its sidewalls 40, 41 and its bottom wall 43 in intimate parallel relation with the corresponding walls of the forward extension of the connection member 32. Thus, the intermediate conduit 22 may swing upon the horizontal, transversely extending shaft 39 without loss of fuel.

The forward end portion of the intermediate conduit 22 is provided with a spherical portion 44 which is received by a similar portion 45 of the riser conduit 21 at the lower end thereof, and is retained in this portion by a split clamp 46.

thereby forming a ball and socket connection at this point. The riser conduit inclines forwardly and upwardly from this connection and delivers fuel through the firing opening 13 of the back-head 12 to which the riser conduit is rigidly secured as by means of the support bracket 47. The upper end of the riser conduit forward wall 48 extends into the firing opening and supports a pressure fluid head 49 which serves to distribute fuel over the firebed from the distributing table 50 as delivered thereto by the riser conduit of the conveying system S.

Suitable means for advancing fuel through the conduits are provided and include a screw conveyor such as 51 which is revolvably mounted in the trough members 20 and universally connected as at 52 to a screw conveyor 53 of the intermediate conduit 22, the screws being universally connected at the joint between said transfer conduit and said intermediate conduit. The conveyor screws are driven in the usual manner, as by a motor connected to gearing at the rear of the trough 20, not shown.

In the modified form shown in Figure 3, a screw conveyor 54 is mounted within the riser conduit 21. This screw is universally connected to the screw 53 of the intermediate conduit 22 as at 55, preferably at the joint between these conduits. A bearing 56 may be provided for the upper terminus of the screw 54.

It will be apparent that a fuel conveying system of novel form has been provided which has ample means for providing for the necessary vertical and horizontal movement between the locomotive and tender units of the stoker when the locomotive and tender are negotiating curves, cross-overs or turntables. This is accomplished by mounting the trough member 20 to swing about a vertical axis or shaft 27 and move longitudinally of the tender by means of the slot 26 in the bracket 25 to provide for any horizontal movement of the trough member. The vertical movement between the riser conduit 21 and the trough member 20 is provided by universally connecting the forward end of the intermediate conduit 22 to the rearward portion of the riser conduit 21 and mounting the rearward portion of the intermediate conduit to swing upon a horizontal transversely extending shaft 39 passing through the novel connecting member 32 of the trough 20.

The function of the modified form of the invention is the same as that of the preferred form, the modified form illustrating but one of the advantages of this novel arrangement of the conduit system. By the use of this modified form of the invention, it is possible to support the upper terminus of the screw 54 of the riser conduit 21 by a bearing 56 without the use of any telescoping sections in the screw conveyors. This is accomplished by permitting the trough members to move longitudinally with respect to the tender 15, thereby maintaining a constant length of the fuel conveying system S from the riser conduit 21 rearwardly.

65 I claim:

1. In a locomotive provided with a firebox having a firing opening therein and a tender for said locomotive, a stoker comprising a transfer conduit on said tender pivotally mounted upon a vertical axis, mounted for slidale movement longitudinally of the tender and fixed with reference to movement about a horizontal transverse axis, a riser conduit attached to said locomotive and arranged to deliver fuel through said firing opening, and an intermediate conduit section

flexibly connected at its ends to said riser conduit and said transfer conduit.

2. In a locomotive provided with a firebox having a firing opening therein and a tender for said locomotive, a stoker comprising a transfer conduit on said tender pivotally mounted upon a vertical axis, mounted for slidale movement longitudinally of the tender and fixed with reference to movement about a horizontal transverse axis, a riser conduit attached to said locomotive and arranged to deliver fuel through said firing opening, and an intermediate conduit section connecting said riser conduit and said transfer conduit, one end of said intermediate conduit being jointed to said riser conduit and the other end thereof being jointed to said transfer conduit to swing upon a transversely extending axis.

3. In a locomotive provided with a firebox having a firing opening therein and a tender for said locomotive, a stoker comprising a transfer conduit on said tender pivotally mounted upon a vertical axis, mounted for slidale movement longitudinally of the tender and fixed with reference to movement about a horizontal transverse axis, a riser conduit attached to said locomotive and arranged to deliver fuel through said firing opening, and an intermediate conduit section connecting said riser conduit and said transfer conduit, one end of said intermediate conduit being universally jointed to one of said named conduits and the other end thereof being jointed to the other of said named conduits to swing upon a transversely extending axis.

4. In a locomotive provided with a firebox having a firing opening in the backhead thereof and a tender for said locomotive, a stoker comprising a transfer conduit on said tender pivotally mounted upon a vertical axis, mounted for slidale movement longitudinally of the tender and fixed with reference to movement about a horizontal transverse axis, a riser conduit secured to said backhead and delivering through said firing opening, and an intermediate conduit section connecting said riser conduit and said transfer conduit, one end of said intermediate conduit being universally jointed to said riser conduit and the other end thereof being jointed to said transfer conduit to swing upon a transversely extending axis.

5. In a locomotive provided with a firebox having a firing opening in the backhead thereof and a tender for said locomotive, a stoker comprising a transfer conduit on said tender pivotally mounted upon a vertical axis, mounted for slidale movement longitudinally of the tender and fixed with reference to movement about a horizontal transverse axis, a riser conduit secured to said backhead and delivering through said firing opening, an intermediate conduit section connecting said riser conduit and said transfer conduit, one end of said intermediate conduit being universally jointed to said riser conduit and the other end thereof being jointed to said transfer conduit to swing upon a transversely extending axis and fixed with reference to movement about a vertical axis, and screw means for advancing fuel through said conduits.

6. In a locomotive provided with a firebox having a firing opening in the backhead thereof and a tender for said locomotive, a stoker comprising a transfer conduit on said tender pivotally mounted upon a vertical axis, mounted for slidale movement longitudinally of the tender and fixed with reference to movement about a horizontal transverse axis, a riser conduit attached to said locomotive and arranged to deliver fuel through said firing opening, and an intermediate conduit section

zontal transverse axis, a riser conduit secured to said backhead and delivering through said firing opening, an intermediate conduit section connecting said riser conduit and said transfer conduit, one end of said intermediate conduit being universally jointed to said riser conduit and the other end thereof being jointed to said transfer conduit to swing upon a transversely extending axis and fixed with reference to movement about a vertical axis, a screw in said transfer conduit and a screw in said intermediate conduit, said screws being universally connected adjacent their ends in coincidence with the joint between said transfer conduit and said intermediate conduit.

7. In a locomotive provided with a firebox having a firing opening in the backhead thereof and a tender for said locomotive, a stoker comprising a transfer conduit on said tender pivotally mounted upon a vertical axis, mounted for slidable movement longitudinally of the tender and fixed with reference to movement about a horizontal transverse axis, a riser conduit secured to said backhead and delivering through said firing opening, an intermediate conduit section connecting said riser conduit and said transfer conduit, one end of said intermediate conduit being universally jointed to said riser conduit and the other end thereof being jointed to said transfer conduit to swing upon a transversely extending axis and fixed with reference to movement about a vertical axis, and a screw in each of said conduits, said screws being universally connected at their adjacent ends in coincidence with the joints in said conduits.

8. In a locomotive provided with a firebox having a firing opening in the backhead thereof and a tender for said locomotive, a stoker comprising a transfer conduit on said tender pivotally mounted upon a vertical axis, mounted for slidable movement longitudinally of the tender and fixed with reference to movement about a horizontal transverse axis, a riser conduit secured to said backhead and delivering through said firing opening, an intermediate conduit connecting said riser conduit and said transfer conduit, one end of said intermediate conduit being universally jointed to said riser conduit and the other end thereof being jointed to said transfer conduit to swing upon a transversely extending axis and fixed with reference to movement about a vertical axis, and a screw in each of said conduits, said screws being universally connected at their adjacent ends in coincidence with the joints in said conduits, the screw in said riser conduit being supported by a bearing adjacent its upper end.

9. In a stoker for use with a locomotive having a tender and a fuel bin, a fuel transfer conduit mounted beneath the fuel bin, a bracket rigidly secured to said tender, said bracket being provided with a longitudinally extending slot, a saddle member formed with said transfer conduit, said saddle member being disposed intermediate the ends thereof and having a flat plate-like portion thereof resting upon the bracket, a vertically extending shaft passing through said flat-plate-like portion of said saddle member and the slot in said bracket whereby said transfer conduit may rotate about said shaft and slide longitudinally with reference to the tender, and adjustable means engaging said shaft whereby the adjacent faces of said flat plate-like portion of said saddle member and said bracket are maintained in contact with each other.

10. In a locomotive and tender, the combina-

tion of a stoker feed conduit system comprising a forward conduit section rigidly secured on the locomotive, a rearward conduit section pivotally mounted on the tender to swing horizontally about a vertical axis and mounted for slidable movement longitudinally of the tender, said rearward conduit being fixed with reference to movement about a horizontal transverse axis, an intermediate conduit interposed between the named sections to form a continuous sectional conduit, and means for flexibly attaching the ends of said intermediate conduit section to the respective forward and rearward conduit sections to permit vertical and transverse movement between said forward and rearward conduit sections.

11. In a locomotive and tender, the combination of a stoker feed conduit system comprising a forward conduit section rigidly secured on the locomotive, a rearward conduit section pivotally mounted on the tender to swing horizontally about a vertical axis and being fixed with reference to movement about a horizontal transverse axis, an intermediate conduit section interposed between the aforesaid conduit sections, and means for flexibly attaching the ends of said intermediate conduit section to the respective forward and rearward conduit sections to permit vertical and transverse movement between them, said rearward and intermediate conduit sections arranged with the locomotive and tender to be movable longitudinally with respect to one and fixed against longitudinal movement with respect to the other.

12. In a locomotive and tender, the combination of a stoker feed conduit system comprising a forward conduit section rigidly secured on the locomotive, a rearward conduit section pivotally mounted on the tender to swing horizontally about a vertical axis and being fixed with reference to movement about a horizontal transverse axis, and an intermediate conduit section at one end being pivotally associated with the rearward conduit section to move vertically only with respect thereto and at its opposite end being universally mounted in operative relation with the forward conduit section, said rearward and intermediate conduit sections arranged with the locomotive and tender to be movable longitudinally with respect to one and fixed against longitudinal movement with respect to the other.

13. In a stoker, a feed conduit system comprising a rigidly mounted forward conduit section, a rearward conduit section pivotally mounted to swing horizontally about a vertical axis and being fixed with reference to movement about a horizontal transverse axis, an intermediate conduit section interposed between the aforesaid sections, and means for flexibly attaching the ends of said intermediate conduit section to the respective forward and rearward conduit sections to permit vertical and transverse movement between them.

14. In a stoker, a feed conduit system comprising a rigidly mounted forward conduit section, a rearward conduit section pivotally mounted to swing horizontally about a vertical axis and being fixed with reference to movement about a horizontal transverse axis, and an intermediate conduit section at one end being pivotally associated with the rearward conduit section to move vertically only with respect thereto and at its opposite end being universally mounted in operative relation with the forward conduit section.

JOHN W. MYERS.
